(57) **CLAIM**

The ornamental design for a electronic cigarette, as shown and described.

DESCRIPTION

FIG. 1 is a bottom perspective view of a electronic cigarette design showing my new design.

FIG. 2 is a top perspective view of the electronic cigarette.

FIG. 3 is a front view of the electronic cigarette.

FIG. 4 is a rear view of the electronic cigarette.

FIG. 5 is a left view of the electronic cigarette.

FIG. 6 is a right view of the electronic cigarette.

FIG. 7 is a top view of the electronic cigarette; and,

FIG. 8 is a bottom view of the electronic cigarette.

Any shading and cross-hatching are not features of the design but are utilized to illustrate the surface contours of the electronic cigarette design in the drawings.

The broken lines in the drawings depict portions of the electronic cigarette that form no part of the claimed design.
